UNITED STATES PATENT OFFICE.

BERNARD LUTSKY, OF BROOKLYN, NEW YORK, ASSIGNOR TO JOSEPH S. TUTTMAN, OF NEW YORK, N. Y.

DESIGN FOR A COMBINED NUTCRACKER AND BOTTLE OPENER.

60,929.

Specification for Design.

Patented May 2, 1922.

Application filed August 20, 1921. Serial No. 493,991. Term of patent 3½ years.

To all whom it may concern:

Be it known that I, BERNARD LUTSKY, a citizen of the United States, and a resident of the city of New York, borough of Brooklyn, in the county of Kings and State of New York, have invented a new, original, and ornamental Design for Combined Nutcracker and Bottle Opener, of which the following is a specification, reference being had to the accompanying drawing, forming part thereof.

What I claim is:—

The ornamental design for a combined nutcracker and bottle opener, as shown.

BERNARD LUTSKY.
